(57) **CLAIM**

The ornamental design for a speaker, as shown and described.

DESCRIPTION

FIG. 1 is a front view of the speaker;

FIG. 2 is a rear view of the speaker of FIG. 1;

FIG. 3 is a right side view of the speaker of FIG. 1;

FIG. 4 is a left side view of the speaker of FIG. 1;

FIG. 5 is a top plan view of the speaker of FIG. 1;

FIG. 6 is a bottom plan view of the speaker of FIG. 1;

FIG. 7 is a top perspective view of the speaker of FIG. 1;

FIG. 8 is a bottom perspective view of FIG. 1;

FIG. 9 is a sectional view taken along line 9—9 in FIG. 5; and,

FIG. 10 is a top perspective view thereof.

The broken line showing on the drawing disclosure is for illustrative purposes only and forms no part of the claimed design.
